UNITED STATES PATENT OFFICE.

ALBERT C. FISCHER, OF CHICAGO, ILLINOIS.

EXPANSION JOINT.

No Drawing.

Application filed September 11, 1922. Serial No. 587,610.

To all whom it may concern:

Be it known that I, ALBERT C. FISCHER, a citizen of the United States, residing in Chicago, county of Cook, State of Illinois, have invented a certain new and useful Improvement in Expansion Joints.

My invention relates to bituminous expansion joints for concrete roads, said joints having incorporated therein excelsior in the place of and in substantially the same proportions of the various organic matter, such as fibers, heretofore generally employed for this purpose.

Excelsior is usually cut from kiln dried lumber which contains little rosin. When incorporated in the bituminous material, whether solid or cellular, it has the effect of materially stiffening the bituminous material, which is very desirable, and at the

same time the excelsior forms an economical filler. Moreover, excelsior being made up of wooden shreds of substantially transverse dimensions, affords a compressible filling material.

The bituminous material may be in the physical condition that naturally results from cooling, or it may be rendered cellular as taught in U. S. Letters Patent No. 1,401,974, issued January 3, 1922, to the present inventor.

I claim:

A pre-molded expansion joint for concrete constructions comprising bituminous material having excelsior incorporated therein.

Signed at Chicago, Illinois, this 9th day of September, A. D. 1922.

ALBERT C. FISCHER.
